UNITED STATES PATENT OFFICE.

BERNARD McCUSKER, OF BRIDGEPORT, CONNECTICUT, ASSIGNOR OF ONE-HALF TO GEORGE J. BROWN, OF SAME PLACE.

HAT-WIRE MACHINE.

SPECIFICATION forming part of Letters Patent No. 404,647, dated June 4, 1889.

Application filed September 14, 1888. Serial No. 285,370. (No model.)

To all whom it may concern:

Be it known that I, BERNARD McCUSKER, a citizen of the United States, residing at Bridgeport, in the county of Fairfield and 5 State of Connecticut, have invented certain new and useful Improvements in Hat-Wire Machines; and I do hereby declare the following to be a full, clear, and exact description of the invention, such as will enable others 10 skilled in the art to which it appertains to make and use the same.

My invention has for its object to provide simple and easily-adjusted automatic mechanism for bending and forming wire, a cutter 15 being provided to sever each completed wire as the last operation is completed. This machine is adapted for various uses, and may be adjusted to produce wires of any desired shape or size.

20 In the drawings I have illustrated a machine embodying the principles of my invention, and especially designed for the production of wires for hat-brims, this special machine being sufficient to illustrate the principles of my invention. I have therefore combined in a single machine the mechanisms required to produce hat-wires ready for use as soon as the ends have been joined by the ordinary clasps, or in any suitable manner, and 25 30 have provided the machine with adjustments whereby it may be caused to produce any desired size of wire. The oval may be made wider or narrower, as required, and a greater or less "droop" or "set" may be produced at 35 the front and rear of the completed wires. In order to accomplish these results in the simplest manner possible, I have devised the novel mechanism, of which the following description, in connection with the accompanying drawings, is a specification, numbers being used to denote the several parts.

Figure 1 is a front elevation of the machine complete, the legs being broken away; Fig. 2, a rear elevation; Fig. 3, a plan view; Fig. 4, 45 an elevation of the right end of the machine as seen in Fig. 1; Fig. 5, an elevation of the left end of the machine; Fig. 6, a section on the line $\alpha\alpha$ in Fig. 1, looking toward the left; Fig. 7, a section on the same line looking toward the right; Fig. 8, a detail view of the

cutter, showing the manner in which the jaws are operated; Fig. 9, an end view of the rock-shaft by which the cutter is operated, the jaws being removed; and Fig. 10 is a longitudinal 55 section of the twisting-sleeve detached.

Similar numbers denote the same parts in all the figures.

1 denotes the bed of the machine, which is supported by suitable legs 2.

3 denotes suitable frame-work for the operative parts of the machine, the several parts of said frame-work resting upon the bed. Power is applied to the machine by a belt (not shown) running over belt-wheel 4 on main 65 shaft 5. This shaft is journaled in suitable boxes 6 upon the frame-work and carries a pinion 7, which meshes with a gear-wheel 8 on a shaft 9, journaled under the bed, shafts 5 and 9 both lying longitudinally of the machine. In addition to gear-wheel 8 shaft 9 carries a cam 10 under the bed, a cam 11 at its right end, a gear 12 at the left end outside of gear 8, and a pinion 13 under the bed. The operation of all of these parts will presently 70 be described in detail.

14 and 15 denote, respectively, the upper and lower feed-rollers, each of which is ordinarily provided with a groove to receive the wire. In practice I preferably use a flattened 80 or polygonal wire, the grooves in the feed-rollers being made to correspond substantially with the shape of the wire in cross-section. The upper feed-roller is carried by a short shaft 16, journaled in a yoke 17, the shank 18 85 of which extends backward and is secured in the frame-work by a pivot or pin 19.

20 is a set-screw in the frame-work, the end of which bears against shank 18 to limit its upward movement, this set-screw being the 90 adjustment to determine the pressure of the feed-rollers upon the wire. A check-nut 21 retains the set-screw in position after adjustment.

22 is a pinion on shaft 16, which meshes 95 with a pinion 23 on a shaft 24, which carries the lower feed-roller. This shaft extends longitudinally of the machine and is suitably journaled in the frame-work at opposite ends thereof, as is clearly shown in Figs. 4 and 5. 100 Motion is imparted to the feed-rollers by

means of a pinion 25 at the opposite or left end of shaft 24, which meshes with an intermediate gear 26, carried by a swinging arm 27, the opposite end of which is pivoted on shaft 24. The swinging arm is provided with a curved slot 28, and is locked in position by a screw-pin 29, passing through said slot and engaging the frame-work. The intermediate gear engages gear 12 on shaft 9 and receives motion therefrom. Gear 12 is made wholly independent of gear 8, and may be readily removed from the shaft and a larger or smaller one substituted. In practice a completed hat-wire is formed during each revolution of the main shaft. If longer wires are required, it is therefore necessary to make the feed-rollers feed faster; if shorter wires are required, to make them feed slower, which is accomplished by substituting a larger gear 12 for longer wires and a smaller gear 12 for shorter wires, screw-pin 29 being loosened to permit arm 27 to swing out of the way. When the new gear 12 has been affixed to the shaft, the intermediate gear is placed in engagement therewith and locked in position by tightening up the screw-pin. As already stated, the machine illustrated in the drawings is especially designed for the production of hat-wires.

It will of course be understood by those familiar with the manufacture of hats that different styles of hats require the oval of the wires to be rounder or narrower, as may be, in the horizontal plate, and, furthermore, that what is called "set" is required at the front and rear of the hat-brim—that is to say, the sides of the brim are highest and both ends droop downward, the amount of set in the brims varying greatly in different styles of hats and in different seasons. The desired set is produced in the completed wires by imparting more or less twist to each half of the wires in the process of formation, and the shape of the wires in the horizontal plane is determined by an adjustable device, which I term a "shaping" device, placed directly in front of the feed-rollers.

I will first describe the twisting mechanism:

30 denotes the twisting-sleeve, which is journaled in the frame-work and provided at its outer end with a pinion 31. This sleeve may be secured in the frame-work in any suitable manner. I preferably provide the sleeve with a semicircular groove 32, a pin 33 engaging a hole in the frame-work, and said semicircular groove holds the sleeve firmly in position and at the same time permits free rotation thereof. Within the sleeve is a suitable holding device, by which the wire is held firmly. In the present instance I have shown rollers, and designate them by 34. Stationary contact-points may be used, if preferred. Oscillation is imparted to the twisting-sleeve by means of a segment-gear 35, which meshes with pinion 31. The segment-gear is journaled upon a screw-stud or pin 36, and is provided with a slot 37.

38 is a lever pivoted to a bracket 39 upon the bed. At the upper end of this lever is a slot, 40.

41 is a link the opposite ends of which engage screw-studs 42 in slots 37 and 40. Nuts 43 lock the studs in position after adjustment.

It will be seen that as both ends of the link are made adjustable it is easy to make very slight or very considerable changes in the oscillation of the segment-gear. The lower end of lever 38 is provided with a pin preferably carrying a roller, which engages slot 44 in cam 10. Shaft 9 is timed to make two complete revolutions during each revolution of the main shaft, thus causing the segment-gear to oscillate twice—that is, to make two forward and two backward movements during the formation of each wire.

It will of course be understood that the shaping and cutting mechanisms, which I shall presently describe in detail, may be so timed relatively to the twisting mechanism as to make the ends of the completed hat-wires join either at the side or end of the wire. I contemplate joining the ends of the wire by clasps in the ordinary manner. As my present invention, however, relates only to the machine for forming the wire, I have not deemed it necessary to illustrate either wire or clasp.

The operation of the twisting mechanism is briefly as follows: The feed-rollers act continuously, drawing the wire through the twisting-sleeve, the amount of twist imparted to the wire depending of course upon the amount of oscillation of the sleeve. The feed-rollers, of course, grip the wire with sufficient firmness to feed forward a certain quantity during each revolution of the main shaft. The holding device in the twisting-sleeve, however, merely prevents the wire from turning in the sleeve, compelling it to turn with the sleeve, but at the same time allowing it to be fed forward freely. It will be apparent that the actual twist imparted to the wire is given between the feed-rollers and the holding device. During the forward movement of the twisting-sleeve, the wire being held firmly at two points as it is drawn forward, it is apparent that the wire must be twisted. This movement occupies but approximately one-quarter of the revolution of the main shaft. During the second quarter of the revolution of the main shaft the twisting-sleeve will be making a backward movement. As the wire is held from turning by the feed-rollers and by the holding device in the twisting-sleeve, the coil being placed in any convenient position, (not shown in the drawings,) it follows that during this backward movement of the twisting-sleeve the twist given to the wire by the forward movement will be partially taken out from that portion of the wire which has not passed the feed-rollers, the amount of twist remaining in the wire after passing the feed-rollers depending

of course upon the amount of twist imparted by the forward movement of the sleeve. An instant later—that is, during the third quarter of the revolution of the main shaft—the twisting-sleeve turns forward again, and then backward during the last quarter, thus repeating the operation just described upon the second half of the hat-wire. The wire as it leaves the feed-rollers, and after being acted on by the shaping mechanism which I shall presently describe, will curl first in one direction and then in the other, as the result of the twist which has been imparted to it, this being the set of the completed wire. Should it be desired to give a greater amount of set at the front and rear of the brim, this result may be readily accomplished by giving a greater movement to the segment-gear, thereby imparting a greater oscillation to the twisting-sleeve. Should less set be required, less oscillation is imparted to the twisting-sleeve. The necessary adjustments are readily effected by raising or lowering either or both ends of link 41. Slight adjustment of the oscillation of the segment-gear may occasionally be required in changing from one coil of wire to another, it being of course well known that two coils of wire very rarely possess exactly the same degree of temper.

The shaping mechanism consists of a roller 45, preferably having a groove corresponding with the grooves in the feed-rollers and carried by a lever 46, pivoted to the frame-work. This lever is caused to vibrate, so as to give roller 45 more or less movement in an arc of a circle by the engagement with its inner end of another lever 47, which in turn is vibrated by the engagement of its opposite end with cam 11 upon shaft 9.

In order that I may secure a very fine adjustment of the shaping-roller, or, if required, a great variation in its adjustment, I have provided both ends of lever 47 and the end of lever 46, which is engaged by said lever, with movable contact portions 48, which are made adjustable by set-screws 49. These contact portions may or may not be provided with anti-friction rollers. It will readily be seen that by means of these three adjustable contact portions I am enabled to secure any possible adjustment of the throw of the shaping-roller that may be required. The movements of the shaping mechanism and the twisting mechanism are of course timed to correspond with each other, the shaping-roller making two oscillations—that is, two upward and two downward movements—during the formation of each hat-wire. As the wire passes through the feed-rollers it comes in contact with the shaping-roller and passes upward over it. Each upward movement of the shaping-roller causes the short curve in the wire that belongs at either the front or rear of the hat-wire. During the downward movement of the shaping-roller the wire is curved slightly, but much less than during the

upward movement. The second upward movement forms the bend at the other end of the hat-brim. Should the shape of the wire in the horizontal plane require to be narrow—that is, what is termed a "flat oval"—a greater amount of oscillation is imparted to the shaping-roller by adjustment of contact portions 48 by means of set-screws 49. Should the shape of oval required be more nearly round, the oscillation of the shaping-roller is decreased in the same manner—that is, by adjustment of the contact portions of the levers—which will be clearly understood from Fig. 4.

After the formation of each hat-wire it is severed from the piece by an automatic cutter, the operation of which I will now describe.

50 denotes a tube inclosing a rock-shaft 51. The stationary cutter 52 is made integral with or rigidly secured to the forward end of the tube. The movable cutter 53 is pivoted at the forward end of the tube and is provided with a rearwardly-extending lug 54, which is engaged by a cam 55 on the end of the rock-shaft. It will be noticed that this cam is a curved incline which engages the under side of the lug. When the rock-shaft is turned forward, the cam is forced to ride up the incline, which forces the movable jaw downward past the stationary jaw, thereby severing the wire, the action being that of a pair of shears. The rear end of the tube is secured within a housing 56 upon the frame-work by a universal joint of any suitable construction. I have shown an outer sleeve 57, which is rigidly secured within the housing by set-screws 58. Within sleeve 57 is a sleeve 59, which is secured thereto by set-screws 60 in such a manner as to leave it free to oscillate in the vertical plane. The rear end of tube 50 is secured within sleeve 59 by means of set-screws 61, which permit it to oscillate in the horizontal plane. Any other simple form of universal joint may be used, if preferred. At the rear end of the rock-shaft back of the sleeves is an arm or lug 62, which is engaged by a lever 63, pivoted to the frame-work. The lower end of this lever is engaged by a cam 64 on a disk 65, journaled on a stud 66, projecting inward from one of the legs. A gear 67 is made integral with or secured to cam 64, and meshes with pinion 13 on shaft 9, gear 67 and cam 64 being timed to make one revolution for each two revolutions of shaft 9, thus making the timing of cam 64 the same as the main shaft, so that each wire is severed as soon as formed. In order to insure the most delicate adjustment of the cutting mechanism, I provide each end of lever 63 with contact portions 68, which are adjusted by set-screws 69, as is clearly shown in Figs. 5 and 6. The forward end of the tube lies in a bracket, 70, projecting outward from the frame-work.

It will of course be apparent that when the

machine is running at a high rate of speed, at the instant the cutting action takes place, the tube will be carried forward slightly by the wire. In order to insure the return of the tube to proper position the instant the completed wire is severed, I provide a spring 71, which is connected to the tube and to any stationary portion of the frame-work—for instance, the bracket itself, as shown in the drawings. The operation of the cutting mechanism will be clearly understood from the drawings. (See Fig. 6, in connection with Figs. 8 and 9.) Lever 63 is so pivoted and the parts are so adjusted relatively to each other that after severing a wire the movable jaw is thrown to and retained at its open position by gravity alone, the lower end of lever 63 being always in contact with the periphery of disk 65. At the completion of each revolution of said disk cam 64 engages the lower end of the lever and swings it outward, causing the upper end thereof to engage arm or lug 62 at the rear end of the rock-shaft, which oscillates the latter and closes the movable jaw through the engagement of cam 55 with lugs 54 at the rear end of the movable cutter. The operation of the entire machine is briefly as follows: I have not shown the coil of wire, as it may be suspended in any convenient position and in any suitable manner. The feed-rollers act continuously and draw the wire forward through the twisting-sleeve, which oscillates twice during the formation of each hat-wire. At the rear end of the twisting-sleeve is a holding device, which prevents the wire from turning independently of the sleeve but allows it to pass forward freely. The first movement of the twisting-sleeve acts to twist the wire between the holding device therein and the feed-rollers. As the wire is being constantly drawn forward by the feed-rollers, part of the twisted portion of the wire is not untwisted by the backward movement of the sleeve. This twist causes the wire to curl in one direction or the other after leaving the feed-rollers. These movements are repeated twice during the formation of each hat-wire and give the set or droop at the front and rear of the wire. The shape of the wire in the horizontal plane is determined by a shaping device, which is caused to swing in an arc of a circle just forward of the feed-rollers, said device moving upward and downward twice during the formation of each wire, which gives the short curves at the front and rear of the hat-wires and the longer curves at the sides thereof. At the completion of the formation of each hat-wire it is severed from the piece by an automatic cutter without any stoppage of the operation of the machine.

Having thus described my invention, I claim—

1. In a machine of the class described, the combination, with the feed-rollers, of the twisting-sleeve 30, provided with a holding

device and with a pinion 31, the segment-gear engaging said pinion, the lever 38, the cam for operating said lever, and the link 41, connecting said lever with said segment-gear.

2. In a machine of the class described, the combination, with the feed-rollers, of the twisting-sleeve 30, provided with a holding device and with a pinion 31, the segment-gear engaging said pinion and provided with the slot 37, the link 41, adjustably attached at its forward end to said segment-gear at said slot, the lever 38, to which the rear end of said lever is connected, and the cam for operating said lever.

3. In a machine of the class described, the combination, with the feed-rollers, of the twisting-sleeve 30, provided with a holding device and with a pinion 31, the segment-gear engaging said pinion and provided with slot 37, the lever 38, provided with slot 40, the cam for operating said lever, the link 41, and screw-studs 42 for adjustably attaching said link to said lever and segment-gear.

4. The combination, with the feed-rollers and the shaping-roller, of a lever 46, whereby said roller is carried, a lever 47, engaging lever 46, a rotating cam engaged by lever 47, and adjustable contact portions on said levers, whereby the movement of the shaping-roller may be varied to give any desired shape to the hat-wires.

5. The combination, with the feed-rollers, of a tube provided with a longitudinally-extending stationary cutter, a movable cutter pivoted to said tube and having a lug 54, and a rock-shaft within said tube and provided at its end with a cam engaging said lug to operate said movable cutter.

6. The combination, with the feed-rollers, of a tube provided at the end with a stationary cutter extending lengthwise thereof, a movable cutter pivoted to said tube and provided with a lug 54, a rock-shaft within said tube and having at one end a cam to engage said arm to operate said cutter and provided at its opposite end with an arm, and a rotating disk having a cam to engage said arm to operate said rock-shaft.

7. The combination, with the feed-rollers, of the tube carrying a stationary cutter and a movable cutter pivoted within the tube and having a lug 54, of a rock-shaft within the tube having a cam engaging said lug, a universal joint connecting the tube with the frame-work, a bracket to support the forward end of the tube, and a spring whereby it is retracted to position.

8. In a machine of the character described, the combination, with the feed-rollers, of an oscillating twisting-sleeve provided with a holding device and through which the wire passes to said rollers, a shaping-roller adjacent to said feed-rollers, a vibrating lever to carry said shaping-roller in the arc of a cir-

cle, and a cutting device to sever the wire at predetermined times, and consisting of a tube provided at one end with a longitudinally-extending stationary cutter, a movable cutter 5 pivoted to said tube and having a lug 54, and a rock-shaft within said tube and having at one end a cam engaging said lug to operate said movable cutter.

In testimony whereof I affix my signature in presence of two witnesses.

BERNARD McCUSKER.
